UNITED STATES PATENT OFFICE

LEWIS C. NORTON, OF LOS ANGELES, CALIFORNIA, ASSIGNOR TO NORTON-LASIER CO., OF CHICAGO, ILLINOIS, A CORPORATION OF ILLINOIS

CONNECTION FOR DOORCHECKS

Application filed April 2, 1930. Serial No. 440,904.

The invention relates to connecting arms for door checks and has particular reference to a type of arm for connecting door checks with a single or double acting door.

5 The invention contemplates a form of door connecting arm especially designed for ready and convenient attachment to means previously secured to the door and to a conventional form of door closing and checking device. Connecting arms are adapted to be secured at their pivot end to the central operating shaft of the closing mechanism and adapted for association at their other end with the door, so that the opening and closing movements of the door will be transmitted to the operating shaft in the form of rotary motion.

In the construction of buildings where doors are equipped with closing and checking means, it is customary to install the closing mechanism in the door sill, prior to the installation of the door. It is often found upon connection being made between the door and the device that efficient actuation and operation of the parts is impossible due to the improper aligning of the door check in the sill and also partly due to inaccurate securement of the other parts to the door.

To this end one of the objects of the present invention is to provide a door connecting arm which will allow for slight inaccuracy in installation of the checking and closing mechanism in addition to allowing the door to be subsequently installed and readily connected to such mechanism.

35 A further object is to provide a connecting arm of the type described, which will have a novel form of guiding or track means for associating the arm with the door, the means being provided with a limited range of adjustment in relation to the sides of the door. This adjustable feature is especially advantageous when the arm is applied to double acting doors, as it allows sufficient adjustment 40 of the connection so that, when the checking

and closing device assumes a neutral position, the door will be aligned with the sill.

A yet further object is to provide an arm of the type described with a novel form of end construction, which will allow for ready 50 attachment of the arm to the door after the latter has been completely installed. The end construction being in the form of a socket member also allows the arm to have free movement upon the ball member attached to 55 it in directions to compensate for inaccurate installation of the closing mechanism.

A yet further object is to provide a device of the character described which will be simple in construction, cheap to manufacture and 60 efficient and positive in operation.

With these and various other objects in view, the invention may consist of certain novel features of construction and operation, as will be more fully described and particularly pointed out in the specification, drawing and claim appended hereto.

In the drawing, which illustrates an embodiment of the device and wherein like reference characters are used to designate like 70 parts—

Figure 1 is a fragmentary front elevation of a door equipped with the closing mechanism and employing the connecting arm of the present invention.

Figure 2 is a sectional view taken along line 75 2—2 of Figure 1, and looking in the direction of the arrows.

Figure 3 is an end elevation of the device as shown in Figure 2 and looking towards the 80 right.

Figure 4 is a perspective view showing the end of the arm provided with socket attaching means.

Figure 5 is a perspective view of the sliding block.

Referring to the drawing it will be noted that the present invention is adapted to be associated with a conventional type of door closing and checking mechanism 10, having 90

a depending central shaft 11. The closing mechanism is of the type employing spring means for imparting closing movements to the door and also employing a fluid dash-pot 5 for checking at the desired point the closing movements. For operation of the mechanism the opening and closing movements of the door must be transmitted to the shaft 11 in the form of rotary movement. As the closing device constitutes no part of the present invention, it will not be further described in detail.

The connecting arm 12 is adapted to be fixedly secured at its pivot end to the depending portion of shaft 11. The securing means may comprise a plurality of screws wherein the arm may be fixedly secured to the shaft and also may be detached therefrom when desired. The other end of the arm is secured to 20 means on the door and for this purpose is provided with a socket portion. A longitudinally extending slot 13 is formed in this end terminating at a point 14. This slot divides the end portion of the arm into a plurality 25 of finger portions, which portions are curved at their extremities into socket forming members 15 and 16 respectively. The inner surfaces 18 and 19 of the socket forming members are slightly dished so that the portions 30 15 and 16 form a ball engaging means. For adjusting the width between the members 15 and 16 an adjustable screw 20 is provided, having a nut 30 fixedly secured thereon and located in the slot 13. The threaded end 31 35 of the screw 20 is threaded into the portion 15 while the opposite end is rotatable in opening 32 in portion 16. It is thus seen that by applying a wrench to the head of screw 20 and rotating the same in one direction that the portions will be spread apart, whereas rotation in the opposite direction will serve to draw the portions together. In this manner adjustment of the ball engaging portions can 40 be secured without removing the arm 12 from shaft 11.

A sliding block 21 is provided adapted to have sliding engagement within a slide guide 22 located in the recess 23 in the door. In forming this recess in the door it is necessary to cut a portion of the door away when the device is adapted to be attached to double acting doors. However, with single acting doors it is only necessary that the recess be provided in one side. The slide guide 22 located in this recess is pivotally secured at one end by a screw 24 and is adjustably supported in position at the other end by a series of threaded members 25. For this adjustable 50 feature it is necessary that the recess be made of such a shape, wherein the end of the recess at 24 is made substantially narrower than the end at which the screws 25 are located. This allows, by adjustment of the screws 25, the 55 guide 22 to be located at any point in the re-

cess which may be desired for proper functioning of the connecting arm.

The sliding block 21 is adapted to have 60 slideable engagement within the slide guide 22 and for purposes of having the arm 12 detachably secured to it, is provided with a stem 26 terminating in a ball portion 27. The ball portion 27 is made of a size substantially equal in diameter to the socket portion formed by the socket members 15 and 16, so that upon adjustment of the screw 20 this socket portion can be readily connected so as to have 70 proper interengaging relation with the ball 75 27.

The installation of the checking mechanism is generally completed long before the door is hinged in place. Before hinging the door in place however, it is desirable when equipping the same with the mechanism of the present invention to provide the recess 80 23 therein and adjustably secure in place the slide guide 22. The door can then be hinged in place and the connecting arm 12 readily secured to the parts by reason of the detachable construction comprising the socket engaging members 15 and 16. It is only necessary to spread the members and fit therein the ball portion 27 of the sliding block 21. Rotation of the screw 20 in the proper 85 direction serves to close the members to cause 90 them to engage the surfaces of the ball 27.

It is therefore seen that by the novel form of connecting arm of the present invention the installations of the checking and closing mechanism and the door can be completed before it is necessary to connect the operative 100 parts of the mechanism with the door. By reason of the socket forming members on the end of the arm 12, ready connection and disconnection can be made between the parts whenever desired. This ball and socket connection between the arm 12 and the sliding block 21 also allows for inaccurate installations of the closing mechanism 10 as the 105 arm 12 may have free movement upon the ball portion 27 without causing a twisting or distortion of the remaining operative parts.

Also the construction of the slide guide 22 is such that relative movement between the slide and door can be had so as to locate the slide in proper position in relation to the checking installation. In those instances where the latter installation is off line the adjustment of the position of the slide guide 115 functions to allow accurate location of the door with the sill.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claim.

I claim:

In combination with a door closing and checking device having a shaft, an arm secured to the shaft, the other end of the arm being provided with a socket portion, a slide guide mounted in a recess in said door, means for adjustably locating said guide within the recess, a block adapted to slide within the guide, and means on the block for association with the socket portion of said arm.

Signed at Los Angeles, California, this 25 day of March, 1930.

LEWIS C. NORTON.
